UNITED STATES PATENT OFFICE.

HERMAN F. ENSRUD, OF BUTTE, MONTANA.

SHOE CABINET.

Application filed March 25, 1927. Serial No. 178,817.

The present invention relates to improvements in receptacles, and has reference more particularly to a shoe cabinet.

One of the important objects of the present invention is to provide a shoe cabinet which is of such construction as to receive a number of pairs of shoes, the supporting shelves for the shoes being arranged within the cabinet in such a manner as to utilize the entire space for accommodating a large number of pairs of shoes.

Another important object of the invention is to provide a shoe cabinet wherein the shelves are disposed in superposed staggered relation, the shelves being furthermore of such construction as to provide angular compartments to accommodate the pairs of shoes placed within the cabinet, the inner end of each shelf being disposed upwardly and in spaced relation with respect to the adjacent side of the receptacle.

A further object of the invention is to provide a shoe cabinet of the above mentioned character which is simple in construction, strong and durable, and further well adapted to the purpose for which it is designed.

Other objects and advantages of the invention will become apparent during the course of the following detailed description, taken in connection with the accompanying drawing.

In the drawing, forming a part of this application, and in which like reference characters indicate like parts throughout the views:

Figure 1 is a front elevation of the shoe cabinet embodying my invention.

Figure 2 is a fragmentary front elevation of a modification of the shoe cabinet.

Figure 3 is a detail perspective view of one of the shelves forming a part of the modified structure and

Figure 4 is a detail perspective view of one of the supporting brackets also forming a part of the modified construction.

In the drawing, with reference more particularly to Figure 1, there is disclosed a shoe cabinet which comprises a substantially rectangular shaped receptacle designated by the numeral 1, the same being open at its front side.

Arranged within the receptacle are the vertically spaced shelves 2. Each shelf is of a length less than the width of the receptacle and is of substantially the same depth as the

receptacle. The outer end of each shelf is secured to the respective side wall of the receptacle in any suitable manner and furthermore these shelves are arranged in staggered relation as is readily obvious from the construction disclosed in Figure 1.

The inner end of each shelf is disposed upwardly as at 3 and the upwardly disposed end is secured to the bottom of the next adjacent shelf in any desirable manner.

The arrangement of the shelves in the manner as shown and above described provides a plurality of angular shaped compartments 4 for receiving pairs of shoes and as shown in dotted lines in this particular figure of the drawing, the toe portions of the shoes are disposed adjacent the upwardly disposed inner end of each shelf while the vertical portions of the angular compartments provide a means for accommodating the shoe uppers.

By arranging the shelves in the manner as above described, the entire space within the receptacle will be utilized to provide compartments whereby a number of pairs of shoes may be placed in the cabinet and supported on the shelves in such a manner as to permit the same to be readily inserted or removed from the several compartments. The cabinet is provided further with sliding drawers 5 and 6 respectively, it being understood, of course, that these drawers are arranged in the upper and lower corners of the cabinet which spaces cannot be utilized for the purpose of providing compartments for additional pairs of shoes.

If desired, a suitable cover or the like may be provided for the open front side of the cabinet, in order that the same will not present an unsightly appearance.

In Figure 2 there is shown a modification of the shoe cabinet wherein the shelves may be readily inserted or removed from within the receptacle and to this end there is arranged on the bottom of the intermediate portion of the shelf 7 a tongue or rib 8, which is arranged transversely of the shelf. Secured to the inner face of the rear wall of the cabinet are a series of channeled U-shaped brackets 9. The base or crown portion of each of the U-shaped brackets is disposed vertically and is secured to the rear wall of the receptacle and the arms 10 and 11 respectively extend for

wardly in a horizontal manner. The inner face of the opposed side walls of the receptacle are formed with transversely extending channels or grooves such as are shown at 16 and the outer end of each shelf 7 is 5 slidable in the respective channel or groove 12, the tongue or rib 8 formed on the bottom face of each shelf being slidable within the lower channeled arm 11 of the respective 10 U-shaped bracket 9, in the manner as clearly shown in Figure 2. The upwardly disposed inner end 13 of each shelf is also adapted for slidable cooperation with the channeled upper arm 10 of one of the U-shaped brackets 9 and in order to permit 15 this arrangement, there must necessarily be two rows of vertically arranged brackets and thereby means is provided for rigidly supporting the shelves in vertically spaced 20 and staggered relation within the receptacle and yet the shelves can be readily removed from the receptacle in a simple and efficient manner.

The provision of a shoe cabinet of the 25 above mentioned character provides a compact device for holding a large number of pairs of shoes and the shoes are arranged within the cabinet in such a manner as to enable a person to readily remove any particular pair of shoes desired, without necessarily interfering with the other pairs placed in the cabinet.

While I have shown the preferred em-

bodiment of my invention, it is to be understood that various changes in the size, 35 shape and arrangement of parts may be resorted to, without departing from the spirit of the invention or the scope of the appended claims.

What I claim is:

1. In a shoe cabinet, a receptacle open at one side, a series of shelves arranged in vertically spaced relation in the receptacle, said shelves being further staggered, each shelf comprising a base of a length less than 40 the width of the receptacle, the inner end of the base being disposed upwardly for engagement with the base portion of the next adjacent shelf whereby a plurality of angular shaped shoe receiving compartments are formed.

2. In a shoe cabinet, a receptacle open at one side, a series of angular shelf forming members arranged in vertically spaced and staggered relation within the receptacle, the outer ends of the horizontal portions of the angular shelves being supported by the sides of the receptacle, and means within the intermediate portion of the back wall of the receptacle for supporting the inner portion 60 of the horizontal portion of the angular shelves as well as the vertical portions of the angular shelves.

In testimony whereof I affix my signature.

HERMAN F. ENSRUD.
